FUSED DISCONNECTING PLUG

Eugene M. Marchand, Bristol, Conn., assignor
to The New Departure Manufacturing Com-
pany, Bristol, Conn., a corporation of Con-
necticut

Application January 12, 1931. Serial No. 508,024

18 Claims. (Cl. 200—115.5)

This invention relates to fused, disconnecting plugs and comprises all the features of novelty herein disclosed. An object of the invention is to provide an improved disconnecting plug and 5 fuse holder which is convenient of access, compact and simple in construction. Another object is to provide a fuse holder which will effectively guard the fuse and protect the workman against electrical shock besides being useful as 10 a disconnecting plug which will allow the safe renewal of fuses. To these ends and to improve generally upon devices of this character, the invention also resides in the various matters hereinafter described and claimed.

15 In its broader aspects the invention is not necessarily limited to the specific construction selected for illustrative purposes in the accompanying drawings in which

Fig. 1 is a plan view of the fused, disconnecting 20 plug.

Fig. 2 is a side view.

Fig. 3 is a section on line 3—3 of Fig. 1 with parts in front elevation.

Fig. 4 is a sectional view on line 4—4 of Fig. 2.

25 Fig. 5 is a top view of the central block.

Fig. 6 is an end view of the central block.

Fig. 7 is a cross sectional view of the central block.

30 Fig. 8 is an outer side view of an end block.

Fig. 9 is an inner side view of the end block.

Fig. 10 is a side elevation of the end block.

Fig. 11 is a plan view of an end cap.

Fig. 12 is an inner side view of the end cap.

35 Fig. 13 is a perspective view of a socket piece.

Fig. 14 is a perspective view of a spring socket piece.

The fuse holder comprises a central block or body 2 partly over-lapping end blocks 4 and 6 which are closed by end caps 8, all preferably 40 of moulded bakelite. The central block is provided through the center with one or more fuse openings 12 each of which tapers or enlarges in opposite directions from the center. The block 45 is supported in any suitable way, as by a rod 14 fixed to a bracket 16 and extending through a cross hole 18 in the block (and through another block or fuse holder 20 for smaller capacity fuses if desired) to receive a wing nut 22. The block 50 2 also has a supporting lug 24 to enter a hole in the bracket, and if a second fuse holder 20 is desired, the latter will also have a supporting lug 26 (Fig. 2) to enter a hole 28 in the block 2.

The block 2 is provided with a number of brass 55 inserts 30 moulded in diagonally spaced holes in

the block and tapped to receive the ends of fastening screws for the end block 4 or 6.

Each end block 4 or 6 has an extended rim portion 32 fitting in or telescoping with a similarly shaped rim or extension 34 of the block 2. One 60 side of each end block has one or more hexagonal recesses 36 aligned with the fuse openings 12. A metal socket piece 38, which is externally hexagonal, fits freely in each recess 36 of the end block 4, the socket piece comprising a cup having a 65 gas relief opening 37 and an axially projecting holding stud 40 which projects through a hole 42 into an irregular recess or cut-out part 44 of the block 4. The studs are threaded to receive securing nuts 46 and are extended to form binding 70 posts for the terminals of electrical load conductors 48 which are fastened by binding nuts 50. Each socket piece 38 is internally threaded to screw onto the threaded end of a standard renewable type cartridge fuse 52 from which the 75 usual end cap has been removed, the usual fuse link abutting against the bottom of the socket piece. The internal construction of the other end block 6 is similar to that of the block 4 but the hexagonal recesses receive spring socket 80 pieces 54 having spring fingers 56 which yieldingly embrace the adjacent caps of the fuses 52. The spring socket pieces 54 are fastened in the recesses by bolts 60 which also form binding posts for other electrical conductors, these last being 85 the terminals of the line wires.

The cut-out portions 44 of the end blocks 4 and 6 form passages for the electrical conductors which are further separated from one another by the triangular lug or extension 62 and the larger 90 extension 64. The lugs have countersunk openings 66 to receive the above mentioned fastening bolts which are threaded into the tapped inserts 30. Such bolts are desirably omitted however from the block 4 which carries the socket pieces 95 38, thereby to provide for easy and safe replacement of fuses. The electrical conductors are covered by the recessed end caps 8 which have dowel pins 68 entering openings 70 in the end blocks. The caps are secured by screw bolts 72 (Figs. 2 and 3) which enter tapped openings in brass inserts 73 (Fig. 8) moulded in holes in the end blocks. The end blocks and end caps are further fastened together by clamping bolts 74, the blocks and caps mating together at their 100 lower ends and forming threaded sockets 76 holding the usual spiral cables 78 which encase the electrical conductors.

The central block 2 together with the end block 6 and its cap 8 are desirably permanently united 110

to guard the spring socket pieces and the line terminals. To get at the fuses, the other end block 4 and its cap 8, together with the socket pieces 38 and fuses 52, can be pulled away, the fuses slipping out from the spring fingers and through the tapered openings 12. Fuses are easily and safely replaced in the socket pieces and the renewed structure can be readily reassembled, the tapered openings 12 guiding the fuses back into the central block. The fuses are always well protected and cannot be touched by the workman until the whole end structure which carries all the fuses is so far withdrawn that the electrical connections are broken between all of the fuses and their spring sockets. Thus, the device also acts as a disconnecting plug as well as a fuse holder and guard. Easy access to fuses is enhanced inasmuch as the spring sockets and threaded sockets can be interchanged together with the line and load conductors to make either end structure removable. The removable end block 4 and its cap are firmly held to the central block by the grip of the spring fingers on the fuses and by the frictional fit of the rim 32 within the rim or extension 34, the edges of the rim 32 preferably having the inclined gas relief ports shown in Fig. 10.

I claim:

1. In a device of the character described, an insulating center block having an opening therethrough, insulating end blocks having socket pieces aligned with the opening, electrical conductors connected to the socket pieces, and a fuse secured to one of the socket pieces and extending through the opening of the center block to detachably engage the other socket piece; substantially as described.

2. In a device of the character described, an insulating center block having an opening therethrough, insulating end blocks having socket pieces aligned with the opening, electrical conductors connected to the socket pieces, a fuse secured to one of the socket pieces and extending through the opening of the center block to detachably engage the other socket piece, and one of the end blocks having a portion telescoping with the center block and removable therefrom with the fuse; substantially as described.

3. In a device of the character described, an insulating center block having an opening therethrough, insulating end blocks having socket pieces aligned with the opening, means for securing the socket pieces to the end blocks, the end blocks having their outer sides recessed, electrical connectors extending through said recesses and connected to the socket pieces, and a fuse secured to one of the socket pieces and extending through the opening of the center block to detachably engage the other socket piece; substantially as described.

4. In a device of the character described, an insulating center block having an opening therethrough, insulating end blocks having socket pieces aligned with the opening, electrical conductors connected to the socket pieces, a fuse secured to one of the socket pieces and extending through the opening of the center block to detachably engage the other socket piece, the end blocks being recessed for the conductors, and end caps secured to the end blocks and covering the conductors; substantially as described.

5. In a device of the character described, an insulating center block having an opening therethrough, insulating end blocks having socket pieces aligned with the opening, electrical con-

ductors connected to the socket pieces, a fuse secured to one of the socket pieces and extending through the opening of the center block to detachably engage the other socket piece, the end blocks being recessed for the conductors, end caps secured to the end blocks and covering the conductors, and the end blocks and end caps having mating portions forming sockets for cable encasing the conductors; substantially as described.

6. In a device of the character described, an insulating block having a fuse opening, a fuse in the opening, a socket piece yieldably engaging one end of the fuse and having connection to electrical conductors, a socket piece secured to the other end of the fuse, an insulating end block having a recess for said last socket piece, means for securing the socket piece to the end block, and the end block having an overlapping and detachable engagement with the other block; substantially as described.

7. In a device of the character described, in combination, a standard cartridge fuse, a spring socket piece to engage one end of the fuse, a socket piece replacing the usual cap at the other end of the fuse and comprising an internally threaded cup screwed on the fuse and having an axially projecting threaded stud, an insulating end block having a recess receiving the threaded cup and a communicating opening for the threaded stud, an electrical conductor, and means on the stud for securing the cup in the recess and for securing the conductor to the stud; substantially as described.

8. In a device of the character described, an insulating center block and insulating end blocks, a fuse extending through the center block from one end block to the other, a socket piece in each end block to engage an end of the fuse, one of the socket pieces having spring fingers and the other comprising an internally threaded cup, and the socket pieces fitting interchangeably in sockets of the end blocks; substantially as described.

9. In a device of the character described, an insulating center block and insulating end blocks, a fuse extending through the center block from one end block to the other, a socket piece in each end block to engage an end of the fuse, one of the socket pieces having spring fingers and the other comprising an internally threaded cup, the socket pieces fitting interchangeably in sockets of the end blocks, and the end blocks being interchangeable and having portions overlapping the center block; substantially as described.

10. In a device of the character described, an insulating center block having a plurality of tapered openings therethrough, insulating end blocks interfitting with the ends of the center block, the end blocks having recesses on their inner sides aligning with said openings, socket pieces in said recesses and having studs projecting through the end blocks into recesses in the outer sides of the end blocks, electrical conductors extending through said recesses to the studs, end caps covering said conductors, and fuses extending through the tapered openings from one set of socket pieces to the other; substantially as described.

11. In a device of the character described, a plurality of fuse blocks, each enclosing a fuse, one side of each fuse block having a supporting lug and the other side of the block having an opening for the corresponding supporting lug of the

- next block, and a supporting rod for the blocks; substantially as described. 80
12. In a device of the character described, an insulating body having a plurality of fuse openings, a fuse in each opening, an insulating end block at the end of the body and having internal recesses aligned with the fuse openings, socket pieces in the recesses and having studs projecting through the end block, the outer side of the end block also having a recess leading laterally to said studs, electrical conductors in said recess and secured to the studs, and insulating projections in the recess to separate the conductors; substantially as described. 85
13. In a device of the character described, an insulating body having a plurality of fuse openings, a fuse in each opening, an insulating end block at the end of the body, socket pieces aligned with the openings and engaging the fuses, the socket pieces having studs projecting through the end block, the outer side of the end block having a recess leading laterally to said studs, electrical conductors in said recess and secured to the studs, and insulating projections in the recess and separating the ends of the conductors; substantially as described. 90
14. In a device of the character described, an insulating body having a fuse opening, a fuse in the opening, an insulating end block having a socket piece aligned with the opening and engaging the fuse, a stud projecting from the socket piece through the end block, the outer side of the end block having a recess leading laterally to said projecting stud, and an electrical conductor in said recess and secured to the stud; substantially as described. 95
15. In a device of the character described, an insulating body having a fuse opening, a fuse in the opening, an insulating end block having a socket piece aligned with the opening and en- 100
16. In a device of the character described, an insulating body having a fuse opening, a fuse in the opening, an insulating end block at the end of the body and having an internal recess aligned with the fuse opening, a socket piece in the recess and engaging the fuse, the socket piece also having a stud projecting through the end block into an external recess thereof, and an electrical conductor in the recess and secured to the stud; substantially as described. 105
17. In a device of the character described, an insulating body having a fuse opening, a fuse in the opening, an insulating end block at the end of the body and having an internal recess aligned with the fuse opening, a socket piece in the recess and engaging the fuse, the socket piece also having a stud projecting through the end block into an external recess thereof, an electrical conductor in the recess and secured to the stud, and an insulating cap covering the conductor and the stud; substantially as described. 110
18. In a device of the character described an insulating body having a fuse opening, a fuse in the opening, an end block having a socket piece aligned with the opening and engaging the fuse, an electrical conductor connected to the socket piece, the end block being externally recessed for the conductor, an end cap covering the recess, and the end cap and end block having mating portions forming a screw socket for a cable enclosing the conductor; substantially as described. 115
